UNITED STATES PATENT OFFICE

2,363,519

DOMESTIC APPLIANCE

Donald K. Ferris, Dayton, Ohio, assignor to General Motors Corporation, Dayton, Ohio, a corporation of Delaware

Application August 14, 1941, Serial No. 406,882

11 Claims. (Cl. 38—54)

This invention relates to domestic appliances, and more particularly to ironers.

An object of this invention is to provide an ironer of the portable type capable of ironing flat work and wearing apparel in an improved manner.

Further objects and advantages of the present invention will be apparent from the following description, reference being had to the accompanying drawings wherein a preferred form of the present invention is clearly shown.

In the drawings:

Fig. 1 is a vertical cross-section, partly in elevation, of an ironing machine embodying features of my invention;

Fig. 2 is a horizontal cross-section taken along the line 2—2 of Fig. 1;

Fig. 3 is a vertical cross-section taken along the line 3—3 of Fig. 1;

Fig. 4 is an elevation of a modified form of the invention;

Fig. 5 is an elevation of another modified form of the invention;

Fig. 6 is a horizontal cross-section taken along the line 6—6 of Fig. 5;

Fig. 7 is a vertical cross-section taken along the line 7—7 of Fig. 5;

Fig. 8 is an enlarged detailed view of a portion of Fig. 5;

Fig. 9 is a drawing showing a modified form of small shoe applicable to all the embodiments previously referred to.

Fig. 10 is an enlarged horizontal cross-section of a portion of Fig. 2.

An ironing machine embodying my invention, comprises, in general, a power driven roll or rotatable member 10, and a plurality of cooperating shoes 11 and 12 movable into contact with said roll 10 by means of physical power derived from the user or operator of the machine.

The shoes 11 and 12 are preferably so related to each other that they may be used together for the purpose of ironing flat work or the like, and yet they may be used separately for special operations as hereinafter more fully described. Preferably the shoe 11 is relatively large in size and the shoe 12 is relatively small in size. The shoe 12 is particularly efficient in performing operations which heretofore have been more readily performed with hand irons, such as the ironing of collars of shirts, cuffs, etc. The shoes 11 and 12 are provided with substantially parallel edges 13 and 14 which are placed at an angle to the path of movement of the roll. The purpose of this is to prevent the seam formed by the edges

13 and 14 from leaving an imprint on any material passing through the ironer.

The ironer may be provided with a base 15. The base 15 may be provided with an upstanding post 16 at the top of which there is provided motor housing 17. The motor housing is provided with an extension 18 provided with one or more bearings 19 and 20 on which the cantilever rotatable shaft 21 is mounted. The roll 10 is mounted on the shaft 21 by means of discs or spiders 22 and 23. The shaft 21 is driven by the motor 24 through the medium of speed reduction gearing 25. The motor 24 is also provided with a fan 26 to circulate air through the housing 17 to cool the motor. Because of the small amount of power required to operate my improved ironer, the motor 24 may be of relatively small size. If desired, it may be of the capacitor type, the condenser being mounted at 27.

The shoes 11 and 12 are rockably mounted, so that they can be rocked to and from the roll 10 selectively or together. For this purpose, the shoe 11 is mounted on an arm 30 supported on a hollow rockable shaft 31. The other end of the hollow shaft 31 is provided with a lever or handle 33 having a disc-like enlargement 34 adapted to receive the hand, forearm or elbow of the user. By pressing down the disc 34, the shoe 11 is locked into engagement with the roll 10. If desired the arm 30 may support the shoe 11 by any well-known spring support 35 now well-known in the art, and which need not be described in detail.

The shoe 12 may be supported on an arm 36, similar in construction to arm 30, and carried by the rock shaft 37, which shaft passes through the hollow shaft 31 and is provided at the other end with a lever or handle 38. The handle 38 may also be provided with an enlarged disc 39, similar to the disc 34, but preferably extending to a point somewhat nearer the user than the disc 34. By this construction, the user may place his forearm or hand on both the disc 34 and 39, if he wishes, causing both shoes 11 and 12 to be brought into contact with the roll 10. He may also select which of the shoes he desires to bring into contact by pressing down only the corresponding disc 34 or 39. The rock shafts 37 and 31 are carried by stationary bearings 40, 41 and 42 supported on the base 15.

The shoe 12 preferably has a shape such that small articles may be readily ironed by said shoe with the roll 10. For this purpose the shoe 12 is provided with a point 43 extending further to one side than the trailing edge of the shoe. The purpose of this is to enable the user to operate

the shoe 12 close to a seam of the article being ironed without danger that the edge 14 may spoil the work after it has passed point 43. The outer edge of the small shoe 12 may be flat as indicated at 44 in Fig. 1; or it may be curved as indicated at 45 in Fig. 9. The curving of the edge at 45 in Fig. 9 is particularly advantageous in ironing collars and the like, since it is possible to bring the shoe 12a of Fig. 9 close to the seams around the collar and also presents a narrower point at 43a.

In Fig. 4, a modification is shown in which the rock shafts 31 and 37 may be eliminated. In this construction, the roll 10b may be driven by a motor, substantially as shown in Fig. 1, the motor being contained in the motor housing 17b supported by a pedestal 16b carried by a base 15b. The interior of the roll 10b and its supports may be substantially as indicated in Fig. 1. The relatively large shoe 11b may be supported by a rockable arm 30b. The arm 30b is rockably supported on a stationary fulcrum 50. The shoe 11b is provided with a handle 51, which the user may grasp and pull forward toward the user to bring the shoe 11b into contact with the roll 10b. The weight of the shoe 11b retracts the shoe when the handle 51 is released. If desired, a spring may be provided to retract the shoe. Likewise the small shoe 12b may be supported on an arm 36b, which is supported in a stationary fulcrum 52 carried by the base 15b. The small shoe may be provided with a handle 53, which the user may bring forward whenever it is desired to bring shoe 12b into contact with roll 10b. The shoe 12b is retracted similarly to shoe 11b.

Means may be provided for tying the shoes 11b and 12b together, so that actuation of either of the handles 51 or 53 alone causes both shoes to be brought into contact with the roll. For this purpose, lugs 54 and 55 are provided in shoes 11b and 12b respectively, and these are connected by means of a pin 56, which ties the two shoes together and causes them to operate as a single shoe.

In the modification shown in Figs. 5 to 8 inclusive, means are provided whereby the first actuation of the handle or pedal 60 causes the small shoe 12c first to come into contact with the roll 10c. Thereafter, upon further movement of the handle or pedal 60, the relatively large shoe 11c is brought into contact with the roll 10c. By this construction, the user may iron relatively small articles with the small shoe 12c, by depressing the handle or pedal 60 partially; but if he desires more ironing surface, he may cause both shoes to be pressed against the roll merely by depressing the handle or pedal 60 to its full extent.

To accomplish this, the roll 10c is mounted substantially the same as shown in Fig. 1 and is carried by a motor housing 17c supported on a pedestal 16c carried by the base 15c, all substantially as shown and described with regard to Fig. 1. The roll 10c is motor-driven the same as in Fig. 1. The large shoe 11c is carried by an arm 30c substantially as shown in Fig. 1, which is supported on a hollow rock shaft 31c; the other end of which is provided with a lever 61. The small shoe 12c is carried by an arm 36c supported on a rock shaft 37c, which passes through the hollow rock shaft 31c and to the other end of which is secured a lever 62. The rock shafts 31c and 37c are supported in stationary bearings 40c, 41c and 42c carried by base 15c.

Downward actuation of the lever 61 locks the large shoe 11c against the roll 10c. Downward actuation of the lever 62 locks the small shoe 12c against the roll 10c.

6 The handle or pedal 60 cooperates with the levers 61 and 62 in such a manner that partial downward movement of the pedal 60 first rocks lever 62 downward, and further downward movement of the handle or pedal 60 then rocks the lever 61 downward. To accomplish this, the upper end 63 of the pedal 60 is provided with a cross bar 64 secured to the outer ends of the levers 61 and 62. A slight play is provided between the pedal 60 and the bar 64 and also between the bar 64 and the levers 61 and 62 to permit a slight differential movement between the levers 61 and 62. Automatic stop means are provided which permit the lever 62 first to descend, and thereafter, upon further movement permits the lever 61 to descend. For this purpose a movable bar 65 is placed underneath the levers 61 and 62. This bar slides in stationary bearings 66 and 67, and is pulled to the left, as shown in the drawings, by means of a tension spring 68. One end 69 of the bar is bent upward to hold the lever 61 in its upper position. The other end 70 of the bar 65 is provided with a slanting surface 71, which permits the lever 62 to move downward a certain distance without releasing the lever 61; but if the lever 62 is moved a sufficient distance, then the end 69 of the lever 65 is moved from under the lever 61, by the action of lever 62 on surface 71, and permits lever 61 to be rocked downward. By the foregoing construction, the first downward movement of pedal 60 causes the lever 62 to be rocked downward a sufficient distance to bring the shoe 12c into contact with the roll 10c, and a further downward movement of the pedal 60, permitted by the usual spring support between the arm 36c and the shoe 12c, causes the shoe 11c to be brought into contact with the roll 10c.

The small shoes 12, 12b and 12c may, if desired, be shaped as shown in Fig. 9. The motor 45 24 may be controlled by a suitable hand switch, not shown, and conveniently mounted either on the housing 17, 17b or 17c, or on the bases 15, 15b or 15c, or may be started by a switch 72 which is closed by the downward movement of the levers 33, 38, 61 and 62, or by the rocking of arms 30b and 36b.

Since there are times when one desires to use the ironer for ironing fabrics without moving the fabrics under the shoe so as to avoid putting a sheen on the fabrics, it is necessary to be able to press the shoe against the roll without closing the switch 72. The relationship of the switch 72 and the shoe operating levers is such that initial movement of a shoe operating lever moves 55 the shoe operated thereby into engagement with the roll but does not close the switch. In order to close the switch, the shoe operating lever must be moved still further.

As shown in Figs. 1, 2 and 3, latches 75 may be 65 provided for holding the levers 34 and 39 down, when desired. The latches 75 are normally ineffective and in order to make the same effective, it is necessary to press the shoe operating lever down and thereafter slide it sidewise so as to 70 catch the lever under the latch.

In the operation of the ironer, the articles to be ironed are placed on the roll 10, 10b or 10c and the small shoe alone, the large shoe alone, or both are brought forward, thus starting rotation of the roll. If small intricate articles are

to be ironed, the small shoe may be used alone. For larger articles, the large shoe may be used alone or in combination with the small shoe, as desired.

The levers 33 and 38 have two parts 33a, 33a and 33b, 38b, respectively joined by vertical pins 33c and 38c, respectively. This permits the portions 33b and 38b to have a slight lateral play, but no relative vertical play, so that they may be depressed and moved under the latches 15. If desired, the portions 33b and 38b may be provided with a slight spring bias (such as by a leaf spring 38d, secured to member 38a and pressing against the lever 38) tending to rotate them in a counterclockwise direction about the pins 33c and 38c against a stop, so that normally they are held in a position to clear the latches 15 in their downward movement, and can be held under the latches by friction, against the slight spring bias, when it is desired to maintain the shoes locked against the roll.

This application is related to my copending application S. N. 282,228 filed June 6, 1939 wherein the advantages of construction of a small shoe and large shoe are fully set forth.

While the form of embodiment of the invention as herein disclosed, constitutes a preferred form, it is to be understood that other forms might be adopted, all coming within the scope of the claims which follow.

What is claimed is as follows:

1. An ironer comprising a rotatable ironing member, a plurality of shoe ironing members, a motor drivingly connected to said rotatable ironing member, means deriving its power from an element actuated solely by physical effort of the operator for moving one only of said shoe members and said rotatable member together, and said means being so constructed and arranged that additional effort transmitted to said element by the operator will move both of said shoe members and said rotatable member together.

2. An ironer comprising a rotatable ironing roll presenting an ironing surface of predetermined length, a motor drivingly connected to said roll, two rock shafts adjacent said roll, a long shoe of shorter length than said predetermined length of said ironing surface oscillatably supported on one of said rock shafts, a short shoe oscillatably supported on the other of said rock shafts, means associated with said rock shafts for selectively moving said short shoe alone or both of said shoes into ironing relation with said roll, and said long shoe and said short shoe cooperating with one another to provide aligned complementary portions of a compound shoe member having an ironing surface substantially equal to but not longer than the ironing surface presented by said roll when both shoes are moved into ironing relation with said roll.

3. An ironer comprising a rotatable ironing member presenting an ironing surface of predetermined length, a motor drivingly connected to said rotatable member, a long ironing shoe of shorter length than said predetermined length of said ironing surface, a short ironing shoe, means for moving said short shoe alone or both of said shoes into ironing relation with said rotatable member, switch means operated by said first named means for energizing said motor, and said long shoe and said short shoe cooperating with one another when both shoes are brought into ironing relation with said rotatable member to provide aligned complementary portions of a compound shoe member having an

ironing surface equal to but not substantially longer than the ironing surface presented by said rotatable member.

4. An ironer comprising a rotatable ironing member presenting an ironing surface of predetermined length, a motor drivingly connected to said rotatable member, a long ironing shoe of shorter length than said predetermined length of said ironing surface, a short ironing shoe, means for moving said short shoe alone or both of said shoes into ironing relation with said rotatable member, switch means operated by said first named means for energizing said motor, and said long shoe and said short shoe cooperating with one another when both shoes are brought into ironing relation with said rotatable member to provide aligned complementary portions of a compound shoe member having an ironing surface substantially equal to but not longer than the ironing surface presented by said rotatable member, the relationship of said first named means to said switch means being such that initial movement of said first named means moves the shoes into ironing relation with said rotatable member and further movement energizes said switch means.

5. An ironer comprising, a long ironing shoe, a short ironing shoe, a rotatable padded member of predetermined length adapted to carry work to the front of and under said shoes, means for rotating said rotatable padded member, means deriving its power solely from physical effort of the operator for moving said short shoe alone or both of said shoes into ironing relation with said padded member, and said shoes cooperating with one another when used together to form aligned complementary portions of a compound shoe member presenting a straight relatively continuous front to oncoming work and having an ironing surface substantially equal to but not longer than the predetermined length of said padded member.

6. An ironer comprising, a long ironing shoe, a short ironing shoe, a rotatable padded member of predetermined length adapted to carry work to the front of and under said shoes, means for rotating said rotatable padded member, means deriving its power solely from physical effort of the operator for moving said short shoe alone or both of said shoes into ironing relation with said padded member, said shoes cooperating with one another when used together to form aligned complementary portions of a compound shoe member presenting a straight relatively continuous front to oncoming work and having an ironing surface substantially equal to but not longer than the predetermined length of said padded member, said shoes having parallel meeting edges disposed at an acute angle to the path of rotation of said padded member to prevent the formation of creases in the work when both shoes are used together and the leading edge of the small shoe being wider than its trailing edge to provide a laterally extending corner thereon.

7. An ironer comprising a rotatable ironing member, a large ironing shoe, a small ironing shoe, a motor drivingly connected to said rotatable ironing member, means deriving its power from an element actuated solely by physical effort of the operator for moving said small shoe only and said rotatable member together, and said means being so constructed and arranged that additional effort transmitted to said element by the operator will move both of said shoes and said rotatable member together.

8. An ironer comprising a rotatable ironing member of predetermined length, a long ironing shoe of substantially shorter length than said predetermined length of said rotatable member, a short ironing shoe, a motor drivingly connected to said rotatable ironing member, means deriving its power from an element actuated solely by physical effort of the operator for selectively moving said short shoe alone or both of said shoes and said rotatable member together, and said long shoe and said short shoe cooperating with one another to form aligned complementary portions of a compound shoe member substantially equal to but not longer than said predetermined length of said rotatable member when both shoes and said rotatable member are brought together in ironing relation.

9. An ironer comprising a rotatable ironing member presenting an ironing surface of predetermined length, a long ironing shoe of substantially shorter length than said predetermined length of said ironing surface, a short ironing shoe, a motor drivingly connected to said rotatable ironing member, means deriving its power from an element actuated solely by physical effort of the operator for selectively moving said short shoe alone or both of said shoes and said rotatable member together, and said long shoe and said short shoe being in horizontal alignment and cooperating with one another when both shoes and said rotatable member are brought together in ironing relation to form complementary portions of a compound shoe member

having an ironing surface substantially equal to but not longer than the ironing surface presented by said rotatable member.

10. An ironer comprising, a long ironing shoe, 5 a short ironing shoe, a rotatable ironing member adapted to carry work to the front of and under said shoes, means for rotating said rotatable member, means deriving its power solely from physical effort of the operator for moving said short shoe alone or both of said shoes and said rotatable member together, said long shoe being substantially shorter than said rotatable ironing member, both shoes being aligned in the direction of the axis of said rotatable ironing member, and 15 said two shoes being not longer than the rotatable ironing member.

11. An ironer comprising, a rotatable ironing member, a long ironing shoe, a short ironing shoe, means for rotating said rotatable member, means 20 deriving its power solely from physical effort of the operator for moving one only of said shoes and said rotatable member together, a manipulator for applying power to said last named means, said means being so constructed and arranged that additional power transmitted to said manipulator by the operator will move both shoes and said rotatable member together, and said long shoe and said short shoe cooperating with 25 one another to form aligned complementary portions of a compound shoe member when both shoes and said rotatable member are brought together in ironing relation.

DONALD K. FERRIS.

CERTIFICATE OF CORRECTION.

Patent No. 2,363,519.

November 28, 1944.

DONALD K. FERRIS.

It is hereby certified that error appears in the printed specification of the above numbered patent requiring correction as follows: Page 3, second column, line 1, claim 3, after the word "not" strike out "substantially" and insert the same before "equal", same line; and that the said Letters Patent should be read with this correction therein that the same may conform to the record of the case in the Patent Office.

Signed and sealed this 27th day of February, A. D. 1945.

Leslie Frazer
